Fig. 13

FIG. 1 is a front perspective view of a coin stand showing my new design;

FIG. 2 is an exploded front, top and right side perspective view;

FIG. 3 is a front elevational view;

FIG. 4 is a right side elevational view, the left side being a mirror image thereof;

FIG. 5 is a top plan view;

FIG. 6 is a bottom plan view;

FIG. 7 is a rear elevational view;

FIG. 8 is a front perspective view of a coin stand showing my new design wherein all the base edges are beveled;

FIG. 9 is a front elevational view of the coin stand shown in FIG. 8;

FIG. 10 is a right side elevational view of the coin stand shown in FIG. 8, the left side being a mirror image thereof;

FIG. 11 is a top plan view of the coin stand shown in FIG. 8;

FIG. 12 is a bottom plan view of the coin stand shown in FIG. 8; and

FIG. 13 is a rear elevational view of the coin stand shown in FIG. 8.

I claim:

The ornamental design for a coin stand, substantially as shown.
